UNITED STATES PATENT OFFICE

153,089

DESIGN FOR A JACKET OR SIMILAR ARTICLE

Samuel Scheidlinger, Jackson Heights, N. Y.

Application December 20, 1947, Serial No. 143,261

Term of patent 3½ years

(Cl. D3—4)

To all whom it may concern:

Be it known that I, Samuel Scheidlinger, a citizen of the United States, residing in Jackson Heights, county of Queens, State of New York, have invented a new, original, and ornamental Design for a Jacket or Similar Article, of which the following is a specification, reference being had to the accompanying drawing, forming part thereof.

In the drawing:

Fig. 1 is a front view of the jacket embodying the design;

Fig. 2 is a rear view; and

Fig. 3 is a fractional view drawn to an enlarged scale showing the ornamentation on the front of the jacket in greater detail.

The essential feature of my design resides in the combination on the jacket disclosed of the specific ornamentation appliqued to the breast portions as shown.

I claim:

The ornamental design for a jacket or similar article, substantially as shown and described.

SAMUEL SCHEIDLINGER.
